SEPARABLE CONNECTER MEANS

Herman Bleibtreu, Darmstadt, Germany, assignor to Freyn Engineering Company, Chicago, Ill., a corporation of Maine

Application October 19, 1935, Serial No. 45,703

11 Claims. (Cl. 173—363)

The present invention relates to separable connector means.

In connection with electrical devices drawing heavy current it is desirable in many instances to provide readily separable connector means between the current drawing device and one or more of the electrical conductors carrying the current for said device. Devices have been known and used for the purpose which comprise an elongated stud adapted to fit more or less closely within a cylindrical hole, the stud being mounted in a handle by means of which the device may be manipulated. Some of the devices referred to have employed a stud split longitudinally and have been capable of a certain amount of springing movement about an imaginary axis, or axes, disposed transversely of the elongated stud. Such devices have left much to be desired in the way of providing good electrical contact between the elongated stud and the wall of the cylindrical hole into which said stud is intended to fit.

An object of the present invention is to provide improved separable connector means involving an elongated stud having a fulcrum disposed lengthwise of said stud, whereby circumferential torsional stresses in the stud may be utilized for providing good electrical connection between said stud and the member into which it fits.

30 A further object is to provide an improved separable connector adapted to fit into a cylindrical hole having means for setting up circumferential stresses and a wedging action for assuring efficient contact between said connector and the wall of said cylindrical hole.

35 A further object is to provide a separable connector employing an elongated stud adapted to fit within a cylindrical hole, which is simple and inexpensive to manufacture and which is efficient in service.

40 A further object is to provide an improved separable connector well adapted to meet the needs of commercial service.

45 Further objects will appear as the description proceeds.

Referring to the drawing—

Figure 1 is an exploded view showing a separable connector and a receptacle within which said connector is adapted to fit;

50 Figure 2 is a sectional view taken along the plane indicated by the arrows 2—2 of Figure 1;

Figure 3 is a view similar to Figure 1 but with the separable connector and its receptacle disposed in operative relationship with each other;

55 Figure 4 is a sectional view taken along the

plane indicated by the arrows 4—4 of Figure 2;

Figure 5 is a sectional view taken along the plane indicated by the arrows 5—5 of Figure 3;

Figure 5a is a sectional view similar to Figure 5 but showing a construction which may be preferred where heavy sections of metal are involved and resistance to circumferential torsional stresses may be high;

Figure 6 is a sectional view taken along the plane indicated by the arrows 6—6 of Figure 2; 10

Figure 7 is a sectional view illustrating a modified construction of the separable connector;

Figure 8 is a sectional view taken along the plane indicated by the arrows 8—8 of Figure 7;

Figure 9 is a view similar to Figure 7 but illustrating another modification;

Figure 10 is a sectional view taken along the plane indicated by the arrows 10—10 of Figure 9;

Figure 11 is a view similar to Figures 7 and 9 20 and illustrating a still further modification; and

Figure 12 is a sectional view taken along the plane indicated by the arrows 12—12 of Figure 11.

Referring first to the form of the invention 25 illustrated in Figures 1 to 6, inclusive, the numeral 20 illustrates a separable connector, and the numeral 21 indicates a receptacle for receiving the separable connector 20. The separable connector 20 includes the hand grip 22 of 30 insulating material, which hand grip is provided with an axial bore for receiving the elongated stud 23, one end of which is electrically connected to the conductor 23a. Said stud 23 has a portion extending beyond the hand grip and 35 adapted to fit within a cylindrical aperture of the electrically conductive member 24, which member 24 is electrically connected to the conductor 24a and may be rigidly mounted in the receptacle 21, by any preferred means, in a location to receive the projecting end of the stud 23. 40 The outer extremity of the member 24 may be flared, as indicated by the numeral 25, and the cooperating end of the stud 23 may be rounded off, as indicated by the numeral 26, whereby the stud 23 may be readily piloted into the apertured member 24. The innermost portion of the stud 23 may fit more or less closely within the bore of the hand grip 22, and the innermost end of said stud 23 may be provided with the shoulder 45 50 55 27 adapted to abut longitudinally against a cooperating shoulder of the hand grip 22. Said stud 23 at the region adjacent to the outer end of the hand grip 22 may be screw-threaded for the reception of the nut 28 adapted to abut

- against a cooperating shoulder of the hand grip 22 to hold the stud 23 against longitudinal movement relative to the hand grip 22. A lock nut 29 may be provided for locking the nut 28. The shoulder 27 of the stud 23 may be provided with the flat portion 30 cooperating with a corresponding flat portion of the hand grip 22 to prevent the stud 23 from turning relative to the hand grip 22.
- 10 The end of the stud 23 projecting beyond the hand grip 22 is slotted longitudinally. In the embodiment of the invention illustrated in Figures 1 to 6, inclusive, the slot in the extremity of the stud 23 is V-shaped, as indicated by the numeral 31. Though a V-shaped slot is probably preferable from a manufacturing standpoint, the conformation of the slot may be chosen as desired. The projecting extremity of the stud 23 is slit, as indicated by the numeral 32, which slit communicates with the slot 31. Said slot 31 and the slit 32 provide two bifurcations 33—33 in the projecting extremity of the stud 23, which bifurcations are spaced apart slightly. If preferred, the slit 32 may be displaced from a position symmetrical with a diameter of the stud, whereby one of the bifurcations 33—33 is less resistant to circumferential torsional stresses than is the other. This construction is illustrated in Figure 5.
- 30 Disposed within the slot 31 is the fulcrum member 34, which, in the embodiment of the invention illustrated in Figures 1 to 6, inclusive, takes the form of a wedge, though other forms of fulcrum member 34 may be chosen if desired. Said fulcrum member 34 is held against longitudinal movement relative to the stud 23 by means of the pin 35, which lies within a corresponding hole in the stud 23. Said fulcrum 34 extends into the holes provided by the nuts 28 and 29 and is thereby held in position longitudinally of the separable connector so that it cannot accidentally work its way loose from the separable connector.
- 40 The diameter of the projecting portion of the stud 23 under normal conditions, as shown in Figures 1 and 2, should preferably be slightly greater than the diameter of the cylindrical aperture into which it is adapted to fit. When it is desired to insert the separable connector 20 into the receptacle 21, the projecting end of the stud 23 will be inserted into the member 24, said stud 23 being piloted into position by reason of the flared opening 25 of the member 24 and the rounded extremity 26 of the stud 23. By reason of the fact that the diameter of the projecting portion of the stud 23 is slightly greater than the hole into which it is to fit, it will be necessary to set up stresses in the bifurcations 33—33 to permit entry of the stud 23 into the member 24. According to the principles of the present invention as illustrated in Figures 1 to 6, the bifurcations 33—33 will have circumferential torsional stresses set up therein, the fulcrum 34 operating as an abutment to insure said circumferential torsional stresses, the result being an efficient contact between the outer walls of said bifurcations 33—33 and the cooperating cylindrical wall of the member 24 as the separable connector 20 is moved into the receptacle 21. The separable connector 20 may be removed from the receptacle 21 by a simple pulling movement. In the event that the bifurcations 33—33 have become distorted in service due to rough handling, or other cause, and have been crushed together, the wedge-shaped fulcrum 34 will operate with a wedging action to move said bifurcations to their

proper operative positions as the stud 23 of the connector 20 is inserted into the member 24 of the receptacle 21.

Figure 5a illustrates a construction which will be found advantageous when connectors of large size are required. In said figure a slit 32a is provided along a chord of the stud and normal to said slit, and communicating with it is the wedge-shaped slot 31a. Said slit 32a and said slot 31a provide the bifurcations 33a—33a and the segment 33b. The wedge-shaped fulcrum 34a is located between the bifurcations 33a—33a. Said bifurcations 33a—33a may have a sufficiently low resistance to circumferential torsional stresses to permit the ready manipulation of the device. The chord defining the segment 33b will of course be chosen of a length equal to or less than the diameter of the cylindrical hole in the member 24, so that the stud may be inserted without difficulty into its receptacle.

The embodiment of the invention disclosed in Figures 7 and 8 employs a stud 40, the projecting portion of which is split to provide the bifurcations 41—41 separated slightly by the slit 42. A notch, indicated by the numeral 43, is provided communicating with the cylindrical surface of the stud 40 and with said slit 42. In said notch is located the wedge-shaped fulcrum member 44. Said fulcrum member 44 is wedge-shaped in both longitudinal section and transverse section, as illustrated in Figures 7 and 8, respectively. The notch 43 decreases in depth progressively from a region adjacent to the outer extremity of the stud 40 to a region adjacent to the hand grip 22. Said wedge-shaped fulcrum member 44 is urged outwardly by means of the spring 45 against the shoulder 45a, and is provided with a shoulder 46 adapted to abut against a cooperating portion of the hand grip 22 to prevent loss of said wedge-shaped fulcrum 44. It will be understood, of course, that the spring 45 may be omitted if preferred. The outer surface of the wedge-shaped fulcrum 44 will be substantially flush with the remainder of the cylindrical surfaces of the bifurcations 41—41 when the parts are in normal position. The diameter of the projecting portion of the stud 40 under the conditions referred to will be slightly greater than the diameter of the cylindrical aperture in the member 24 of the receptacle 21.

When the embodiment of the invention illustrated in Figures 7 and 8 is to be inserted into a receptacle such as the receptacle 21, the wedge-shaped fulcrum member 44 will have a triple function. By reason of its friction against the cylindrical wall of the member 24 of the receptacle 21, said wedge-shaped fulcrum 44 will tend to move longitudinally toward the hand grip 22 and radially outwardly, having a wedging action against the cylindrical wall of the member 24. Moreover, said wedge-shaped fulcrum member 44 will have a circumferential wedging action against the bifurcations 41—41, spreading them apart into good electrical contact with the cooperating wall of the member 24 of the receptacle 21. In addition, said member 44 will act as an abutment whereby as the separable connector 20 is inserted into the receptacle 21, circumferential torsional stresses will be set up within the bifurcations 41—41, urging the outer walls of said bifurcations 41—41 into efficient electrical contact with the cylindrical aperture within the member 24. When it is desired to remove the stud 40 from the receptacle 21, a pulling movement will be communicated to the hand grip 22,

whereby the wedge-shaped fulcrum member 44 will be moved longitudinally and radially to a position in which the outer surface thereof is flush, or substantially flush, with the cylindrical walls of the bifurcations 41-41 and the stud 40 may be readily pulled out of the receptacle 21. In the construction illustrated in Figures 7 and 8, the normal diameter of the stud 40 may, if preferred, be less than the diameter of the cylindrical aperture in the member 24.

Referring now to the construction illustrated in Figures 9 and 10, a stud 47 is provided, split transversely to provide two bifurcations 48-48, separated by the slit 48a. Mounted within said stud 47 is the longitudinally extending fulcrum pin 49, disposed preferably in spaced parallel relationship with the axis of the stud 47, which fulcrum pin may be held against longitudinal movement with respect to the stud 47 by any preferred means. As illustrated, the fulcrum pin 49 is provided with the cross pin 50, which cooperates with the stud 47 for holding said fulcrum pin 49 in position. The bifurcations 48-48 are provided with opposed half round surfaces 51-51 for bearing contact with the fulcrum pin 49. The outer cylindrical surfaces of the bifurcations 48-48 will have a diameter slightly greater than the diameter of the cylindrical hole in the member 24 of the receptacle 21. When it is desired to insert the stud 47 within a cylindrical hole such as that in the member 24 of the receptacle 21, a pushing movement will be communicated to the hand grip 22 whereby circumferential torsional stresses will be set up within the bifurcations 48-48 about the axis of the fulcrum pin 49, whereby effective electrical contact will be had between the cylindrical surfaces of said bifurcations 48-48 and the wall of the cylindrical aperture in the member 24. In removing the stud 47 from the receptacle 21, a pulling movement will be communicated to the hand grip 22, whereby said stud 47 may be readily drawn out of said receptacle 21.

Referring now to the embodiment of the invention illustrated in Figures 11 and 12, the hand grip 22 has the stud 55 extending therefrom, which stud is longitudinally slotted for the reception of the longitudinally movable wedge 56. The slot for receiving the wedge 56 has its bottom inclined away from the axis of the stud 55 in the direction toward the hand grip 22. A spring 57 is provided for urging the wedge 56 away from the hand grip 22, whereby the wedge 56 projects radially only so far that its outer radial side surface is substantially flush with the cylindrical surface of the remainder of the stud 55. It will be understood, of course, that the spring 57 may be omitted, if preferred. The diameter of said cylindrical surface will be substantially equal to the diameter of the cylindrical hole in the member 24 of the receptacle 21. Said wedge 56 may be held in place by means of the nut 58, and a lock nut 59 may be provided for holding the nut 58 in place. The inner extremity of the wedge 56 may underlie a portion of the stud 55, to the end that the wedge 56 is held against loss in service. In the construction illustrated in Figures 11 and 12 the projecting stud 55 is not bifurcated. In pushing the stud 55 into the member 24 of the receptacle 21, the wedge 56, due to its friction with respect to the cylindrical wall of the member 24, will slide in its groove, and as said stud 55 is inserted further into the hole in the member 24, said wedge 56 will protrude beyond the cylindrical surface of the stud 55, pre-

senting a tight fit. When the stud 55 is pulled out of the member 24, the wedge 56 will move to its extreme longitudinal position, wherein the outer surface of said wedge 56 is substantially flush with the cylindrical surface of the remainder of the stud 55.

Though certain preferred embodiments of the present invention have been described in detail, many modifications will occur to those skilled in the art. It is intended to cover all such modifications that fall within the scope of the appended claims.

What is claimed is:

1. In connector means, in combination, an elongated stud, said stud having a spacing slit disposed longitudinally thereof to provide bifurcations and having a longitudinal slot communicating with the outer surface of said stud and with said slit, and fulcrum means of non-changing shape in operation in said slot for causing circumferential torsional stresses in said bifurcations when said stud is inserted into a hole of less diameter than the normal diameter of said stud, said fulcrum means being secured to and forming with said stud an approximately cylindrical unit movable into and out of gripping relationship with a cooperating cylindrical socket.

2. In electrical connector means, in combination, an elongated stud of approximately cylindrical contour, said stud having a slot communicating with its surface, a receptacle for receiving said stud, and a wedge-shaped member of non-changing shape in said slot for urging said stud into good electrical contact with said receptacle, said wedge-shaped member being secured to and forming with said stud an approximately cylindrical unit movable into and out of gripping relationship with a cooperating cylindrical socket.

3. In electrical connector means, in combination, an elongated stud of approximately cylindrical contour, said stud having a slot communicating with its surface, a receptacle for receiving said stud, and a wedge-shaped member in said slot for urging said stud into good electrical contact with said receptacle, said wedge-shaped member being of non-changing shape in operation and being wedge-shaped in both longitudinal and transverse section with respect to the cylindrical contour of said stud.

4. In an electrical connector, in combination, a stud of approximately cylindrical contour, a receptacle for said stud, said receptacle having a cylindrical bore of slightly less diameter than the cylindrical contour of said stud, said stud being split longitudinally into a plurality of parts, and fulcrum means of non-changing shape carried by said stud for setting up circumferential torsional stresses in said stud when said stud is inserted into said aperture in said receptacle, said fulcrum means being secured to and forming with said stud an approximately cylindrical unit movable into and out of gripping relationship with a cooperating cylindrical socket.

5. In an electrical connector, in combination, a stud of approximately cylindrical contour, a receptacle for said stud, said receptacle having a cylindrical bore of slightly less diameter than the cylindrical contour of said stud, said stud being split longitudinally into a plurality of parts, and fulcrum means of non-changing shape carried by said stud for setting up circumferential torsional stresses in said stud when said stud is inserted into said aperture in said receptacle, said fulcrum means being wedge-shaped in con-

formation and being secured to and forming with said stud an approximately cylindrical unit movable into and out of gripping relationship with a cooperating cylindrical socket.

- 5 6. In an electrical connector, in combination, a stud of approximately cylindrical contour, a receptacle for said stud, said receptacle having a cylindrical bore of slightly less diameter than the cylindrical contour of said stud, said stud
10 being split longitudinally into a plurality of parts, and fulcrum means of non-changing shape carried by said stud for setting up circumferential torsional stresses in said stud when said stud is inserted into said aperture in said receptacle,
15 said fulcrum means being wedge-shaped in conformation in both longitudinal section and transverse section with respect to said stud.
7. In an electrical connector, in combination, a stud of approximately cylindrical contour, a receptacle for said stud, said receptacle having a cylindrical bore of slightly less diameter than the cylindrical contour of said stud, said stud being split longitudinally into a plurality of parts, and fulcrum means of non-changing shape carried by said stud for setting up circumferential torsional stresses in said stud when said stud is inserted into said aperture in said receptacle, said fulcrum means comprising a fulcrum pin disposed between the split portions of said stud
20 and being secured to and forming with said stud an approximately cylindrical unit movable into and out of gripping relationship with a cooperating cylindrical socket.
8. In connector means, in combination, an elongated stud, said stud having a spacing slit disposed longitudinally thereof to provide bifurcations and having a longitudinal slot communicating with the outer surface of said stud and with said slit, and fulcrum means of non-changing
25 shape in said slot for causing circumferential torsional stresses in said bifurcations when said stud is inserted into a hole of less diameter than the normal diameter of said stud, said fulcrum means being wedge-shaped and being secured to
30 and forming with said stud an approximately cylindrical unit movable into and out of gripping relationship with a cooperating cylindrical socket.

cylindrical unit movable into and out of gripping relationship with a cooperating cylindrical socket.

9. In connector means, in combination, an elongated stud, said stud having a spacing slit disposed longitudinally thereof to provide bifurcations and having a longitudinal slot communicating with the outer surface of said stud and with said slit, and fulcrum means of non-changing shape in said slot for causing circumferential torsional stresses in said bifurcations when said stud is inserted into a hole of less diameter than the normal diameter of said stud, said fulcrum means being wedge-shaped both in transverse and longitudinal section with respect to said stud. 10

10. In connector means, in combination, an elongated transversely collapsible stud having elongated bifurcations, said stud being provided with fulcrum means for setting up circumferential torsional stresses within said stud when said stud is inserted into a hole of less diameter than the normal diameter of said stud, said fulcrum means being of non-changing shape in conformation and being secured to and forming with said stud an approximately cylindrical unit movable into and out of gripping relationship with a cooperating cylindrical socket, said fulcrum means reacting against the wall of said socket and against said bifurcations. 15

11. In electrical connector means, in combination, an elongated stud of approximately cylindrical contour, said stud being slit longitudinally through a portion of its length to provide bifurcations, said stud having a slot communicating with its surface and with the slit between said bifurcations, and a receptacle for receiving said stud, said stud being provided with fulcrum means in said slot for setting up torsional stresses in said bifurcations whereby to urge said bifurcations into good electrical contact with said receptacle, said means being of non-changing shape in operation and being secured to said stud and movable with said stud into and out of gripping relationship with a cooperating cylindrical socket. 30 35 40
